UNITED STATES PATENT OFFICE.

CHARLES M. GIBSON, OF ROCHESTER, NEW YORK.

WINDOW-SASH CONSTRUCTION.

Application filed April 23, 1926. Serial No. 104,079.

This invention relates to a window sash construction, and has for its object to provide a mechanism that permits using the conventional type of vertically sliding counter-balanced sash, while at the same time permitting the glass retaining portion or frame to be swung inwardly so as to permit easy access to the exterior surface of the glass for cleaning.

Another object of the invention is to afford a structure that can be used without changing the usual window frame, and can also be readily incorporated in standard types of window sash by a slight reconstruction thereof.

Still a further purpose of the invention is to provide a structure having comparatively few parts that can be manufactured economically, and which lends itself to easy manipulation of a window.

To these and other ends, the invention consists in the construction and arrangement of parts that will appear from the following description when read in conjunction with the accompanying drawings, the novel features being pointed out in the claims following the description.

In the drawings:

Figure 1 is a front elevation of a conventional window frame with upper and lower window sash built in accordance with a preferred embodiment of the invention;

Figure 2 is a horizontal sectional view on line 2-2 of Figure 1.

Figure 3 is a transverse vertical sectional view on line 3-3 of Figure 2;

Figure 4 is a view similar to Figure 3 with the glass retaining frames swung inwardly;

Figure 5 is a perspective view of one of the glass retaining frames partially broken away;

Figure 6 is a perspective view of the upper part of one of the vertically sliding supporting members;

Figure 7 is an enlarged sectional view taken through a pivot of one of the swinging glass retaining frames, and

Figure 8 is a horizontal sectional view of one of the sliding supporting members.

Referring more particularly to the drawings in which like reference numerals refer to corresponding parts in the several views, 1 designates a window frame of conventional type in which are mounted upper and lower sliding sash as shown in Figure 1. Each sash includes vertically movable slides or

supporting members 2, which are preferably provided with guide members 3, that are fixedly attached and move in suitable ways or grooves formed in the fixed stops 4 or 60 other stationary part of the frame.

5 designates a glass retaining frame carrying a pane 6 and pivoted at 7 to the lower ends of the slidable supporting members 2. The pivotal connection 7 is preferably be-

tween two metal stop plates 8 and 9 which are fixedly attached to the supporting member 2 and glass retaining frame 5 respectively, as shown in Figures 2, 7 and 8. When the frames are in normal or vertical position,

the stop plate 9 that is carried by the glass retaining frame 5 lies between the adjacent surface of supporting member 2 and the overlapping portion of the stop plate 8, as shown in Figures 7 and 8. This arrange-

ment limits the outer movement of the glass retaining frame with relation to the slidable supporting members, and also acts to hold said parts in rigid, tight relationship when the frames are in normal, vertical position, as illustrated in Figures 1 and 3. Each of the slidable supporting members is provided

with a locking device in the form of a catch 10, see Figure 6, that is pivoted between the plate 8 and the body of the supporting member at the upper end thereof. Said catch 10 has an inclined portion 11 and a nose 12 which cooperate with the upper end 13 of the strip 9 on the glass retaining frame.

By moving the glass retaining frame to 90 vertical position and drawing the catches 10 downwardly, the parts are held as illustrated in Figures 1 and 3 and can be operated like the conventional sliding sash. When it is desired to wash one or both windows, the 95 catches 10 on the inside sash are first swung upwardly, and the sash swung inwardly as illustrated in Figure 4. The outside sash can then be lowered and swung inwardly after elevating its catches, occupying a position superposed on the lower sash, as shown in Figure 4.

In order to permit the outside sash to swing inwardly through the opening of the inside sash, the glass retaining frame of the 105 inside sash is made slightly wider than that of the outside sash, as illustrated in Figure 2. This affords an opening that permits the glass retaining frame of the outside sash to clear the sliding supporting members 110 when swung through the opening of the inside sash. By pivoting the glass retaining

frames at the lower ends of the sashes, it is possible to gain easy access to the exterior surface of the glass for cleaning, and there is the added advantage that none of the parts 5 at any time project outside of the window frame. The structure is simple and easy to control, and affords an economical and practical arrangement which can be readily applied to old window frames and built in 10 new windows at a reasonably low cost.

While I have described the invention with reference to certain details of construction, it is not restricted to the precise form shown, and this application is intended to cover 15 such modified arrangements or departures as may come within the spirit of the improvements or the scope of the following claims.

I claim:

20 1. A window sash comprising vertically
slidable supporting members, a glass retaining
frame, stop plates secured to the frame
and supporting members respectively, the
adjacent stop plates being located in dif-
25 ferent vertical planes and arranged to sub-
stantially overlap each other when the frame
is in vertical position, the supporting mem-
bers and frame being recessed under their

respective stop plates to afford openings
which receive the cooperating and overlap-
ping stop plates, and means pivotally con-
necting the stop plates at their lower ends
to permit swinging movement of the frame
about its lower portion.

2. A window sash comprising vertically 35
slidable supporting members, a glass retain-
ing frame, stop plates secured to the frame
and supporting members respectively, the
adjacent stop plates being located in differ-
ent vertical planes and arranged to sub- 40
stantially overlap one another when the
frame is in vertical position, the supporting
members and frame being recessed under
their respective stop plates to afford open-
ings which receive the cooperating and over- 45
lapping stop plates, means pivotally connect-
ing the stop plates at their lower ends to
permit swinging movement of the frame
about its lower portion as an axis, and
catches pivoted between the supporting 50
members and their stop plates and arranged
to engage the cooperating stop plates on the
glass retaining frame.

In witness whereof, I have hereunto signed
my name.

CHARLES M. GIBSON.
